ALBERT H. STEBBINS, OF LOS ANGELES, CALIFORNIA

AIR CLASSIFIER

Application filed April 8, 1930. Serial No. 442,570.

The invention relates to air classifiers of the centrifugal type and more particularly to means for promoting a rotative movement of the air within the classifying receptacle.

5 In air classifiers of this general type it is desirable that the air and materials to be separated be introduced into the receptacle to rotate therein at high speed, and the present invention relates to improvements in the 10 means for introducing the materials and air into the receptacle so that this air stream will impart the desired rotative movement to the volume of air within the receptacle.

An important feature of the present invention therefore resides in means for delivering an air stream into the receptacle in a spiral downwardly extending direction so that it encircles the volume of air within the receptacle throughout a relatively large area and 20 gradually merges with the air within the receptacle to impart its rotative movement to this volume of air.

This desired result is secured in the embodiment of the invention illustrated by providing the air classifying receptacle with an air inlet pipe that extends spirally about the receptacle in a downward direction and is arranged so that its spiral coils extend gradually inwardly through the side of the receptacle and pass from the exterior to the interior of the receptacle, to thereby direct the air stream spirally around the receptacle and guide it along a spiral downwardly extending path within the receptacle.

35 The above and other features of the invention and novel combination of parts will be hereinafter described in connection with the accompanying drawings illustrating one good practical form thereof.

40 In the drawings:—

Fig. 1 is a side elevation of an air classifier constructed in accordance with the present invention;

45 Fig. 2 is a perspective view with parts in section of the lower portion of the air classifier of Fig. 1;

Fig. 3 is a sectional view taken on the line 3—3 of Fig. 1;

50 Fig. 4 is an enlarged sectional view taken on the line 4—4 of Fig. 1, and

Fig. 5 is a vertical sectional view taken on the line 5—5 of Fig. 2.

The classifying receptacle into which air and the materials to be separated are delivered may be variously constructed so that the 55 material laden air may rotate therein to throw the heavier materials outwardly by centrifugal force against the side walls of the receptacle to move downwardly adjacent these walls under the influence of gravity, 60 but in many cases it is desirable to so construct the classifying receptacle that it converges in a downward direction so that the heavier materials are directed inwardly towards the central axis of the receptacle as 65 they move downwardly therein.

In the embodiment of the invention illustrated in the drawings the classifying receptacle has the general downwardly converging construction just mentioned so that the 70 lower portion 10 of the classifying receptacle is relatively small while the upper portion 11 thereof is much larger in diameter and constitutes an expansion chamber in which the air may expand to promote the 75 settling of the heavier particles out of the air stream. The upper annular portion 11 of the receptacle has extending downwardly therefrom the downwardly converging portion 12 and the lower end of this downwardly converging portion 12 is connected to the intermediate or drum-like portion 13, and below this drum-like portion 13 the receptacle is provided with several inwardly stepped portions 14 of reduced diameter as 80 shown.

The upper end of the classifying receptacle is closed and has the exhaust pipe 15 leading from the central portion thereof. This exhaust pipe may lead direct to the 85 suction side of an exhaust fan or may lead to an exhaust pipe 16 as shown.

The materials to be treated may be supplied to the classifier of the present invention by a feed pipe 17 through which air 90 bearing the materials to be treated is advanced along the pipe either by suction or blast means. This material bearing air may be supplied to the pipe 17 from a preceding machine or other source of supply, but in the 100

embodiment of the invention shown the materials to be treated are supplied to the air inlet pipe 17 by a feed hopper 18 having the adjustable gate 19 adapted to regulate the flow of the materials from the feed hopper into the pipe 17. Air from the atmosphere is preferably introduced into the pipe 17 near the feed hopper 18 so that it will help promote the flow of the materials from the hopper into the feed pipe, and in the construction shown the pipe 17 is provided at its outer end with the air inlet apertures 20 through which air is drawn into the pipe by the suction produced within the receptacle 15 by the exhaust pipe 15.

The feed pipe 17 in accordance with the present invention extends spirally about the air classifier in a downward direction and communicates with the receptacle throughout a substantial portion of its length, the arrangement being such that the material laden air stream within the pipe 17 is directed spirally about the classifying receptacle and may gradually move inwardly into the receptacle to merge with the air therein and impart rotative movement to the volume of air.

The feed pipe 17 as shown is formed with a plurality of spirals surrounding the classifying receptacle and these spirals gradually pass inwardly from the exterior to the interior of the classifier so as to guide the air stream in a downward spiral direction after it enters the receptacle.

In the construction shown the stream of air supplied by the feed pipe 17 is confined in this pipe throughout a portion of the uppermost coil and the wall between this spiral coil and the classifying receptacle is cut away at a point indicated by 21 as part way around this upper coil; that is, the air stream is permitted to pass inwardly and intermingle with the volume of air in the classifier from the point 21 downwardly through out the remaining portion of the spirally disposed feed pipe. As above stated the spiral coils of the feed pipe gradually pass inwardly through the wall of the receptacle and the outer curved wall of the spiral pipe merges with the outer wall of the portion 13 of the air classifier at the point indicated by 22. From the point 22 onward the upper spiral wall 23 of the spiral feed pipe is disposed at the inner surface of the classifying receptacle and constitutes a spiral guide for directing the air stream downwardly along its spiral path within the air classifier.

The lower wall 24 of the spiral feed pipe, in the construction shown is secured to the classifying receptacle between the stepped portions 13 and 14 thereof, the arrangement being such that the spaced spirally disposed walls 23 and 24 within the lower portion of the receptacle form a well defined spiral path 65 therein for guiding the air stream down-

wardly within the receptacle into the lower portion thereof as will be apparent from the drawings.

The material laden air drawn inwardly along the feed pipe 17 as a result of the suction produced in the air classifier by the pipe 15, or by blast means (not shown) will be directed downwardly in a spiral path within the classifying receptacle and since this feed pipe is provided with a plurality of spiral coils passing repeatedly around the interior of the receptacle they produce a well defined spiral passage which will serve to direct the air stream downwardly in a spiral path about the volume of air to impart the desired rotative movement to the air within the receptacle. The heavier particles within the air stream will be thrown outwardly against the outer curved wall of the spiral pipe and as they travel downwardly along the different coils of this pipe they will pass from the lower end thereof into the reduced lower portion 10 and then into the collecting hopper 25 from which they may be discharged from time to time in a well known manner.

The portion of the spirally traveling air stream which gradually works inwardly and intermingles with the volume of air within the receptacle will have the heavier particles removed therefrom by the centrifugal action just mentioned, but the larger particles which pass from the air stream into the volume of air in the receptacle will be subjected to a further centrifugal action by the rotative movement of the entire volume of air to further promote the separation of the coarser from the finer particles within the classifying receptacle.

It may be desirable to introduce a small amount of air into the lower portion of the receptacle to pass upwardly therein to thereby produce rising air currents which will help to pick up the lighter particles that may tend to work downwardly into the discharge hopper 25. This is accomplished by providing the lower portion of the receptacle with the air inlet slots or apertures 26, through which air may enter from the atmosphere, and these apertures are preferably so constructed that they will direct the air substantially tangentially into the receptacle to thereby promote the whirling movement of the air within the receptacle.

It will be seen from the foregoing that as a result of the present construction whereby the air stream is guided spirally about the volume of air within the receptacle this air stream is given ample opportunity to impart its rotative movement to the volume of air to cause all the air within the receptacle to rotate rapidly and thereby effect the desired centrifugal separation of the materials being treated.

The materials carried along the feed pipe 17 by the stream of air may tend to settle

along the lower wall 24 of this pipe but this is prevented in accordance with the present invention by providing the pipe with the air inlet apertures 27 through which air may enter from the atmosphere to pick up the particles that tend to settle along the lower wall 24 of the pipe.

What is claimed is:

1. An air classifier, comprising in combination, a downwardly extending receptacle, means for delivering an air stream carrying the materials to be separated into the receptacle with a rotative movement that imparts a rotative whirling movement to the volume of air within the receptacle, including an air inlet pipe extending spirally downwardly about the receptacle and through a side wall thereof to project inwardly from the inner wall of the receptacle, and adapted to guide the stream of material laden air into the receptacle and in a downwardly spiral path therein, and means for removing air from the upper end of the receptacle.

2. An air classifier, comprising in combination, a downwardly converging receptacle, means for delivering an air stream carrying the materials to be separated into the receptacle with a rotative movement that imparts a rotative whirling movement to the volume of air within the receptacle, including an air inlet pipe extending spirally downwardly about the receptacle to guide the stream of material laden air into the receptacle and provided with a downwardly extending spiral portion that projects inwardly from the inner wall of the receptacle to guide the air stream upon entering the receptacle along a downwardly extending spiral path, and means for removing air from the upper end of the receptacle.

3. An air classifier, comprising in combination, a downwardly converging receptacle, means for delivering an air stream carrying the materials to be separated into the receptacle with a rotative movement that imparts a rotative whirling movement to the volume of air within the receptacle, including an air inlet pipe extending spirally downwardly about the receptacle and opening into the receptacle throughout a substantial portion of its spiral length, and means for removing air from the upper portion of the receptacle.

4. An air classifier, comprising in combination, a downwardly extending receptacle, means for delivering an air stream carrying the materials to be separated into the receptacle with a rotative movement that imparts a rotative whirling movement to the volume of air within the receptacle, including an air inlet pipe extending spirally downwardly in a plurality of coils about the receptacle and opening into the receptacle along its spiral length, and means for removing air from the upper portion of the receptacle.

5. An air classifier, comprising in combination, a downwardly extending receptacle, means for delivering an air stream carrying the materials to be separated into the receptacle with a rotative movement that imparts a rotative whirling movement to the volume of air within the receptacle, including an air inlet pipe extending spirally downwardly about the receptacle in communication therewith and provided with a cooperating spiral wall extending inwardly from the inner wall of the receptacle to guide the air stream downwardly in a spiral path, and means for removing air from the upper portion of the receptacle.

6. An air classifier, comprising in combination, a downwardly extending receptacle, means for delivering an air stream carrying the materials to be separated into the receptacle with a rotative movement that imparts a rotative whirling movement to the volume of air within the receptacle, including an air inlet pipe extending spirally downwardly about the receptacle to direct the air stream along a spiral downwardly extending path within the receptacle and provided with air inlet apertures in its lower wall, and means for removing air from the upper portion of the receptacle.

7. An air classifier, comprising in combination, a downwardly extending receptacle, means for delivering an air stream carrying the materials to be separated into the receptacle with a rotative movement that imparts a rotative whirling movement to the volume of air within the receptacle, including an air inlet pipe extending spirally about the receptacle in a downwardly direction and provided with a plurality of coils that pass gradually from the outside to the inside of the receptacle, and means for removing air from the upper portion of the receptacle.

8. An air classifier, comprising in combination, a receptacle having spirally arranged portions that are stepped inwardly to reduce the diameter of the lower portion of the receptacle, means for delivering an air stream carrying the materials to be separated into the receptacle with a rotative movement to impart a rotative whirling movement to the volume of air in the receptacle, including an air inlet pipe extending spirally downwardly about the receptacle and into the interior of the receptacle to cooperate with said spiral stepped portion and adapted to guide the stream of material laden air into the receptacle and downwardly therein along a spiral path, and means for removing air from the upper portion of the receptacle.

In testimony whereof, I have signed my name to this specification.

ALBERT H. STEBBINS.
